UNITED STATES PATENT OFFICE

ARTHUR MUTSCHELLER, OF NEW YORK, N. Y., ASSIGNOR TO WAPPLER ELECTRIC COMPANY, INC., A CORPORATION OF NEW YORK

X-RAY MACHINE

Application filed September 20, 1926. Serial No. 136,420.

My invention relates to X-ray machines of the general type described in my pending application, Serial No. 101,012, filed April 10, 1926, and in which a complete and self-
5 containing X-ray unit, energized by currents supplied to it from an extrinsic source, furnishes rectified currents of high potential, suitable for energizing the main discharge circuit of an X-ray tube, and also furnishes
10 low tension currents for heating the cathode filament of the X-ray tube, as well as the cathode filament of such valve tubes as are used.

More particularly stated, I seek to improve
15 the X-ray machine of the type mentioned, so as to develop relatively high voltages without undue danger to persons or apparatus, and to enable the same machine to be instantly converted, so as to supply either high voltage
20 and a light current or a lower voltage with a heavier current, as desired; all unwieldy parts of the machine, including the valve tubes carried by it, remaining undisturbed in position.

25 In the prior art there has been used an X-ray apparatus containing a high tension transformer, a valve tube and an X-ray tube, so combined as to develop high tension discharges of unitary direction through the X-ray tube. However, with the apparatus just mentioned as heretofore employed, there are severe limitations upon the voltage and current which may safely be used with an X-ray tube, and these limitations have unduly restricted the use of the apparatus of the prior art.

30 In my new machine I have managed, chiefly by the relative arrangement of the various parts, to increase both the voltage and the current, which can be supplied safely to a given X-ray tube, or to any X-ray tube under given conditions. In accomplishing this desirable purpose I have also succeeded in producing a very compact X-ray machine, in which all high tension strains are as far as practicable distributed as uniformly as possible, and so localized that the machine as a whole is comparatively safe to handle.

35 An important feature of my invention is the provision of valve tubes, condensers, a

high tension transformer provided with two separate secondary windings, and a change-over switch, so arranged that a single movement of the switch and the parts actuated therewith has the effect of shifting the machine as a whole from one operating condition to another. That is to say, for the two normal positions of the switch the machine has two distinct conditions of operation. In one of these conditions the secondary windings and the valve tubes are all in series with each other and with the X-ray tube, and the condensers are in active use. In the other of the two conditions the valve tubes are in parallel with each other and the secondary windings are also in parallel with each other with reference to the X-ray tube, and the condensers are short circuited and thus rendered inactive.

40 By having the condensers in active use whenever the secondary windings and valve tubes are in series with each other and with the X-ray tube, a considerable amount of energy can be stored in the condensers, and used for rendering the discharge through the X-ray tube almost continuous. While this might be a hindrance for certain purposes of radiography, by causing the discharge through the X-ray tube to lag and thus increase the difficulty of obtaining short exposures, it is of great value in therapeutic operations.

45 Owing to the compact arrangement of the various parts in my device, most of the mechanism can be submerged in oil. The machine as a whole has generally the form of an oil tank provided with a cover, practically all of the parts not housed within the tank and submerged in the oil being carried upon the cover, and the parts thus carried being as far as practicable those which should in practice be 50 more or less accessible.

55 Reference is made to the accompanying drawings forming a part of this specification, and in which like reference characters indicate like parts throughout the several figures.

60 Figure 1 is a view showing the oil tank serving as a housing and the mechanism contained therein, and is a section on the line

1—1 of Figure 2, looking in the direction indicated by the arrows.

Figure 2 is a section on the line 2—2 of Figure 1, looking in the direction indicated by the arrows.

5 Figure 3 is a section on the line 3—3 of Figure 1, looking in the direction indicated by the arrows.

10 Figure 4 is a plan view of the mechanism shown in Figure 3, with this mechanism as it would appear to a person standing at the left of that figure.

15 Figure 5 is a diagram of the widening, with the mechanism in condition for high voltage and low amperage, the condensers being active.

20 Figure 6 is a diagram of the wiring with the machine in condition for low voltage and heavy currents, the condensers being short-circuited and thus inactive.

25 A tank 7 serves the double purpose of an oil tank and a container for most of the mechanism. This tank is provided with a cover 8, in the form of a flat plate, detachably fitted upon it and serving as a support for a portion of the mechanism.

30 Located within the bottom of the tank and spaced widely apart are a pair of pillow sills 9, 9, and extending upwardly from them are lifting posts 10. Each lifting post is provided with a neck portion 11 extending through a hole in the pillow sill, and secured by a nut 12, as indicated by dotted lines in Figure 2. The lifting posts each extend from bottom to top of the tank and are each provided with an eye 13. There are four of these eyes, and they are useful in lifting the tank and its contents whenever this is desirable.

40 Disposed adjacent the pillow sills 9, 9, and parallel thereto are foot sills 14 of which there are two. Extending crosswise of the pillow sills 9, 9 and foot sills 14, 14 are a pair of tie beams 15, 15, shown more particularly in Figure 3. These tie beams are secured to the pillow sills 9, 9 by means of bolts 16, as may be understood from Figures 1 and 2.

45 A transformer core is shown at 17, and rests upon the tie beams 15, 15, as indicated in Figure 3. Engaging the transformer core are a pair of clamping blocks 18, 18, each provided with a relatively thick portion 19, as indicated more particularly in Figure 2.

50 Bolts 20 of the form shown in Figure 3, each extend through one of the clamping blocks 18, closely adjacent a portion of the transformer core 17, and through one of the tie beams 15 and one of the foot sills 14.

55 Mounted upon the transformer core 17, which is self-closed, are two distinct primary windings 21, 22, and covering each primary winding is a tubular sleeve 23, of insulating material.

60 Encircling the windings 21, 22, are two separate and distinct secondary windings 25,

24, located some distance apart, that is to say, they encircle oppositely disposed portions of the transformer core. Each secondary winding has the form of a double spool.

65 Each foot sill 14, 14, is provided adjacent each of its ends with a number of slots 26, each preferably being a saw kerf, and relatively shallow. Fitted into the slots 26 and thus resting upon the foot sills 14 are a number of condenser plates 27, 28, so arranged as to constitute two distinct condensers, located adjacent opposite ends of the foot sills 14, 14. The condenser plates are provided with rims 29 which fit loosely into the slots 26.

70 Located within the upper portion of the tank is a condenser block 30 of the form shown in Figure 3. It extends entirely across the tank, and is provided with a pair of downwardly extending portions 31, the latter being formed to engage the upper edges of the condenser plates. For this purpose the downwardly extending portions 31 are provided with slots 32, into which the upper edges of the condenser plates extend. Thus the condenser plates are firmly fixed in position, being held at both top and bottom.

75 Conductively connected with the condensers and extending upwardly therefrom are a number of conducting strips 33, 33, arranged in two sets as shown, and at the top 80 connected with the condenser terminals, shown at 34, 35. Similarly a number of condenser strips 36, 36, lead to the condenser terminals 37, 38.

85 Thus one condenser, made up of the plates 27 has its terminals 37 and 38, and the other condenser, made up of the plates 28, has its terminals 34 and 35.

90 A switch base 39, having the form of a plate is mounted upon the clamping blocks 18, and by means of screws 40 is secured directly to the relatively thick portion 19 thereof.

95 Carried by the switch base 39 and extending upwardly therefrom is a rocking shaft 41 made of metal, a stationary post 42 also of metal, and an actuating shaft 43. This actuating shaft is made of metal, and extends through a hole in the cover 8, which acts as a bearing. The actuating shaft 43 is adapted to be rocked. The switch base 39 also carries 100 a metallic post 44 which is stationary and which extends upwardly from it like the post 42.

105 The two shafts 41 and 43 and the two posts 42 and 44 are provided with tubular insulating members 45.

110 Mounted rigidly upon the actuating shaft 43 is a crank 46, and a similar crank 47 is mounted upon the upper end of the rocking shaft 41. A pitman 48 extends from the crank 46 115 to the crank 47, in order to enable these two cranks to be actuated in unison, by rocking movements of the actuating shaft 43.

120 A contact arm 49 is mounted rigidly upon the rocking shaft 41, and another contact arm 125

50 is mounted rigidly upon the actuating shaft 43. A metallic post 61 is located midway between the rocking shaft 41 and the actuating shaft 43.

5 The parts just described are so formed and arranged that when the actuating shaft 43 is turned in a clockwise direction according to Figure 1 the two contact arms 49 and 50 are brought into engagement with the metallic post 61 and thus into metallic communication with each other, and when the actuating shaft 43 is turned in a counterclockwise direction according to this figure, the contact arms 49 and 50 are disengaged from each other, the contact arm 49 being brought into contact with a contact button 51, carried by the metallic post 42 and virtually forming a part thereof, the contact arm 50 being brought into engagement with a contact button 52, carried by 10 the post 44 and constituting practically an enlarged portion thereof.

20 Mounted rigidly upon the upper end of the actuating shaft 43 is a rocking arm 53, of the form shown more particularly in Figure 4. Associated with the rocking arm 53 is an indicator 54, shown more particularly in Figure 4, and provided with legends High and Low, these legends referring respectively to the voltage to be controlled by aid of the actuating shaft 43, or rather by the switch of which this shaft is a part.

25 A cord 55 is connected with one end of the rocking arm 53, and connected with the opposite end of this rocking arm is another cord 56. The cords 55 and 56 are threaded through eyes 57, and are pulled by hand as occasion requires, in order to shift the rocking arm 53 back and forth, thus operating the switch.

30 Mounted upon the cover 8 are a pair of binding posts 58, 59 through which current is supplied to the primary circuit of the transformer, and a binding post 60 which is used as a ground connection. A wire 61 leads from the binding post 60 to the metallic post 61, and by aid of this wire and binding post the post 61 is grounded.

35 Mounted upon the cover 8 and extending upwardly therefrom are four high tension insulators 62, 63, 64 and 65. These insulators are of tubular form, and are provided respectively with neck portions 66, 67, 68 and 69, also of tubular form which project downwardly through holes in the cover. Each neck portion is closed oil tight at its bottom by a closure plate 70 of insulating material.

40 Encircling the neck portion 68 and supported thereby is a small transformer 71, having an annular form and adapted to generate currents of low voltage for heating the cathode or filament of the X-ray tube. Similarly, two other transformers 72 and 73 of the same kind are provided, the transformer 72 encircling the neck portion 67 of the insulator 63, and the transformer 73 being mounted in

the same way upon the neck portion 69 of the insulator 65.

45 The transformers 72 and 73 are each used for generating currents to heat the filament or cathode of one of the valve tubes, of which there are two. These valve tubes are used as rectifiers of the high tension currents, as hereinafter more particularly explained.

50 I do not deem it necessary to describe in detail the construction and action of these 75 transformers, as they form no part of my invention. Suffice it to say that they are energized in any appropriate manner, as for instance by currents supplied from a line, an adequate amount of resistance being used, 80 interposed between them and the line.

55 A pair of valve tubes as shown at 74, 75 are used as rectifiers for the high tension currents.

60 The valve tube 74 is mounted upon the 85 insulator 62, and extends upwardly therefrom with its anode end upward. A metallic sphere 76 is connected with the upper end of this valve tube, and is provided with a high tension tap 77, rounded to prevent 90 corona. This tap serves practically as a high tension binding post. A clip, not shown, is detachably gripped upon it at any time, in order to connect it up with outside mechanism of any kind to which high tension currents are to be supplied. 95

65 A metallic tube 78 is connected with the sphere 76, and serves as a support therefor. This metallic tube is fitted into the upper end of the high tension insulator 65, and extends therefrom obliquely upward to the left 100 according to Figure 3.

70 In much the same manner the valve tube 75 is supported upon the insulator 64, from which it extends upwardly. Above the valve 105 tube 75 is a metallic sphere 79, carrying two taps 80 and 81, like the tap 77. The sphere 79 is mounted upon a metallic tube 82, the latter being mounted upon the insulator 63 and extending therefrom obliquely upward 110 to the right according to Figure 3.

75 The various parts above described are connected up as indicated in the diagrams shown in Figures 5 and 6. The wiring is alike in these two figures, but the condition of the 115 mechanism is different, owing to the action of the high tension switch.

80 An X-ray tube is shown at 83, its anode and cathode ends being indicated by plus and minus signs. The X-ray tube is not housed 120 within or supported by the casing, and may be located at any point convenient for the purpose.

85 From the cathode end of the X-ray tube 83 a conductor 84 leads to a junction 125. From this junction a conductor 86 leads to the condenser 27, another conductor 87 leads to the stationary contact post 42, and another one 88 to the secondary winding 24.

90 From the anode end of the X-ray tube a 130

conductor 88 leads to a junction 89, and from thence three conductors 90, 91 and 92 lead respectively to the condenser 28, the stationary contact post 52 and the secondary winding 25.

From the secondary winding 25 a conductor 93 leads to the cathode end of the valve tube 74. From the anode end of this tube a conductor 94 leads to a junction 95, and thence two conductors 96 and 97 lead respectively to the condenser 27 and the rocking post 41.

A conductor 98 leads from the actuating shaft 43 to a junction 99, and thence a conductor 100 leads to the condenser 28, and a conductor 101 leads to the cathode end of the valve tube 75. The anode end of the valve tube is connected by a conductor 102 with the secondary winding 24.

Two conductors 103 and 104 are connected with the respective binding posts 58 and 59. The conductor 103 is also connected with two conductors 105 and 106, the conductor 105 leading to the primary winding 22, and the conductor 106 leading to the primary winding 21. The conductor 104 is connected with a conductor 107 leading to the primary winding 21, and with another conductor 108 which leads to the primary winding 22. By these connections the two primary windings are in parallel with each other with reference to the binding posts 58 and 59, whereby the primary circuit is energized.

The primary circuit may be traced as follows: source of alternating current (not shown), binding post 58, wire 103, whence the current divides; one half of it passes through wire 105, primary winding 22, wire 108 to wire 104, the other half passing through wire 106, primary winding 21 to wire 104; here the two halves of the current reunite, and pass out through the binding post 59 to source of power. This energizes the transformer, and currents are thus generated in the secondary windings 24 and 25.

The secondary circuit is different at different times, depending upon the condition of the electric switch, as controlled from time to time by the operator, by aid of the two cords 55 and 56.

If the operator wants the machine to generate light currents of relatively high voltage he pulls the cord 55, and thereby brings the electric switch into the condition shown in Figures 1 and 2 and indicated by the diagram in Figure 5.

The secondary circuit through the X-ray tube 83 may now be traced as follows:

X-ray tube 83, conductor 88, junction 89, conductor 92, secondary winding 25, conductor 93, valve tube 74, conductor 94, junction 95, conductor 97, rocking shaft 41, contact arms 49 and 50 (now in contact) actuating shaft 43, conductor 98, junction 99, conductor 101, valve tube 75, conductor 102, secondary

winding 24, conductor 88, junction 85, and conductor 84 back to X-ray tube 83.

It will be noted that the two condensers 27 and 28, while not included in the circuit just traced, are nevertheless each bridged across a part of the circuit, in such manner as to store up considerable quantities of electric energy. This arrangement of the condensers enables the machine to maintain the voltage almost continuous, which is an object of great value for therapeutic purposes.

It may be noted that in the circuit just traced each secondary winding produces one half of the terminal voltage, and each valve tube rectifies one half of the total current. It may also be noted that while the electric stresses due to the high voltage are very great, they are as far as practicable distributed uniformly throughout the system.

When the operator wants to produce relatively heavy currents of lower voltage and to cut out the condensers, he simply pulls the cord 56. This places the machine in the condition indicated by the diagram in Figure 6.

The secondary circuit now has two branches in parallel with each other, and may be separately traced with reference to its two branches as follows: First, X-ray tube 83, conductor 88, junction 89, conductor 92, secondary winding 25, conductor 93, valve tube 74, conductor 94, junction 95, conductor 97, rocking shaft 41, contact arm 49, contact button 51 of stationary post 42, conductor 87, junction 85 and conductor 84, back to X-ray tube 83. Second, X-ray tube 83, conductor 88, junction 89, conductor 91, contact button 52 of stationary post 44, contact arm 50, actuating shaft 43, conductor 98, junction 99, conductor 101, valve tube 75, conductor 102, secondary winding 24, conductor 88, junction 85, and conductor 84 back to X-ray tube 83.

It may be noted that with the machine in the condition indicated in Figure 6, the X-ray tube is energized, first by a current generated in the secondary winding 25 and passing freely through the valve tube 74, and then by a current generated in the secondary winding 24 and passing freely through the valve tube 75; and that whenever current is passing through either valve tube it is never passing through the other.

The arrangement contemplated by Figure 6 is of peculiar value for short exposures with heavy current. For examining the stomach, chest and various other internal organs, this arrangement is ideal. As an independent consideration, the current loads as well as the voltages are here well distributed, and with reasonable care no trouble need occur.

By short-circuiting the condensers and throwing them out of action as indicated in Figure 6, all time-lag due to excessive capacity is done away with, and the time periods of exposure are reduced accordingly.

My improved X-ray machine is adapted for a variety of work, in that it can be instantly converted from one of its functions to the other. It can be used steadily for any 5 length of time for one kind of work, and then used steadily for another kind of work, or it can be shifted back and forth from one kind of work to the other at very short intervals, as desired. Because of its double 10 function, it can often be used instead of two separate machines, one for therapy and the other for radiography.

I do not limit myself to the precise mechanism shown, as variations therefrom may be 15 made without departing from my invention, the scope of which is commensurate with my claims.

Having thus described my invention, what I claim as new and desire to secure by Letters 20 Patent is as follows:

1. In an X-ray machine the combination, with an X-ray tube, of a pair of secondary windings, a rectifying member connected with each winding for rectifying the currents 25 produced thereby, and switch mechanism connected with said rectifying members for connecting them in series or in parallel with each other relatively to said X-ray tube, depending upon the voltage and current required for said X-ray tube.

2. In an X-ray machine the combination, with an X-ray tube, of a pair of secondary windings, a rectifying member connected with each winding for rectifying the currents 35 produced thereby, switch mechanism connected with said rectifying members for connecting them in series or in parallel with each other and to said X-ray tube, according to the voltage and current required for said 40 X-ray tube, and condenser mechanism connected with said secondary windings and controllable by said switch mechanism for throwing said condensers out of action whenever said rectifying members are thus connected 45 in parallel.

3. In an X-ray machine the combination, with an X-ray tube, of a pair of secondary windings, a pair of valve tubes, one for each secondary winding, and a switch connected 50 with both of said secondary windings and both of said valve tubes, said switch having two normal positions, one for connecting said secondary windings and valve tubes in series with each other and the other for connecting them in parallel with each other, to said 55 X-ray tube.

4. In an X-ray machine the combination, with an X-ray tube, of a pair of secondary windings, rectifying devices, condensers, and 60 a switch connected with said secondary windings and with said rectifying devices and condensers, said switch having two normal positions, one for the double purpose of bridging said condensers across said X-ray 65 tube and connecting said secondary windings

and rectifying devices in series with each other relatively to said X-ray tube, the other for the double purpose of throwing said condensers out of action and connecting said secondary windings in parallel with each other relatively to said X-ray tube. 70

5. In an X-ray machine the combination, with an X-ray tube, of a pair of secondary windings, a pair of valve tubes, one for each secondary winding, a pair of condensers, one for each secondary winding, and a switch connected with all of said secondary windings, valve tubes and condensers, said switch having two normal positions, one for the double purpose of connecting said secondary 75 windings and said valve tubes in series with each other relatively to said X-ray tube and bridging said condenser across the same, the other for the double purpose of throwing said condenser out of action and connecting in 80 parallel with each other, relatively to said X-ray tube, two parallel circuits each containing one of said secondary windings and one of said valve tubes.

6. In an X-ray machine the combination, with an X-ray tube, of a plurality of secondary windings, means independent of said X-ray tube for rectifying the currents developed by said secondary windings in order to produce discharges of unitary direction 90 through said X-ray tube, switch mechanism connected with said secondary windings in order to connect them in different ways relatively to said X-ray tube so as to vary the amperage relatively to the voltage of the currents producing said discharges, and condenser mechanism connected with said switch mechanism and controllable thereby for further varying the character of said currents. 95

7. In an X-ray machine the combination, with an X-ray tube, of a plurality of secondary windings, rectifying devices, a switch connected with said secondary windings and said rectifying devices and coating therewith for varying the voltage and amperage of currents supplied to said X-ray tube, and condensers connected with said switch and thereby thrown into and out of circuit with 100 said X-ray tube. 105

8. In an X-ray machine the combination, with an X-ray tube, of a pair of secondary windings, a pair of valve tubes, one for each secondary winding, a pair of condensers, one for each secondary winding, and a switch connected with said condensers for throwing them into and out of circuit, said switch being also connected with all of said secondary windings, valve tubes and condensers for the purpose of enabling said secondary windings to discharge either in series or in parallel through said X-ray tube. 110

9. A device, comprising an X-ray tube, two secondaries for energizing said X-ray tube, and two valve tubes for rectifying the 115 120 125 130

high tension currents generated by said secondaries, one of said secondaries and one of said valve tubes being in circuit with the other secondary and the other valve tube relatively to said X-ray tube.

5 10. In a circuit with an X-ray tube a plurality of secondaries for energizing said X-ray tube, and a plurality of valve rectifiers for rectifying the high tension currents generated by said secondaries, said secondaries being in parallel with each other, and said valve tubes also being in parallel with each other, relatively to said X-ray tube.

15 11. In an X-ray machine the combination, with an X-ray tube, of a plurality of secondary windings, a plurality of rectifiers for rectifying the currents produced by said secondary windings, and switch mechanism controllable by the operator for connecting 20 said rectifiers in parallel with each other relatively to said X-ray tube.

25 12. In an X-ray machine the combination, with an X-ray tube, of a plurality of secondary windings, a plurality of rectifying devices, and a plurality of condensers connected with said secondary windings and said secondary rectifying devices, said condensers being in parallel with each other relatively to said X-ray tube.

30 13. In an X-ray machine the combination, with an X-ray tube, of a plurality of secondary windings, a plurality of rectifying devices, and a plurality of condensers connected with said secondary windings and said rectifying devices, said rectifying devices being in parallel with each other relatively to said X-ray tube.

35 Signed at Long Island City, in the county of Queens and State of New York, this 13th
40 day of September, 1926.

ARTHUR MUTSCHELLER.
